(57) **CLAIM**

The ornamental design for a portion of a packing container, as shown and described.

DESCRIPTION

FIG. 1 is a top perspective view of a portion of a packing container showing my design;

FIG. 2 is a top view of FIG. 1;

FIG. 3 is a bottom view of FIG. 1;

FIG. 4 is a (left/right) side view of FIG. 1;

FIG. 5 is a front view of FIG. 1;

FIG. 6 is a back view of FIG. 1;

FIG. 7 is a detailed top view of FIG. 1 attached to the packing container, corresponding to the section marked in FIG. 2; and,

FIG. 8 is a detailed profile (left/right/front/back) view of FIG. 1 attached to the packing container, corresponding to the section marked in FIG. 4.

The broken lines illustrate environmental features that form no part of the claimed design.
